United States Patent Office

Des. 228,319

Patented Sept. 4, 1973

228,319

ADVERTISING SIGN

Charles H. Winecoff, New York, N.Y., assignor to
Burger Chef Systems, Inc., Indianapolis, Ind.

Filed Dec. 27, 1971, Ser. No. 212,875

Term of patent 14 years

Int. Cl. D20—03

U.S. Cl. D96—12 R

FIG. 1

FIG. 2

FIG. 3

FIG. 4

FIG. 5

FIG. 6

FIG. 1 is a side elevation of an advertising sign, showing my new design;

FIG. 2 is a front elevation thereof, the rear being a mirror image of the front shown;

FIG. 3 is a top plan view of same;

FIG. 4 is a side elevation of a modified form of the advertising sign shown in FIG. 1;

FIG. 5 is a front elevation of FIG. 4, the rear being a mirror image of the front shown; and

FIG. 6 is a top plan view of FIG. 4.

I claim:

A new and ornamental design for an advertising sign, as shown and described.
